CARL SCHRAUBSTÄDTER, OF BROOKLINE, MASSACHUSETTS.

Design No. 4,531, dated December 20, 1870.

DESIGN FOR A TYPE.

The Schedule referred to in these Letters Patent and making part of the same.

I, CARL SCHRAUBSTÄDTER, of Brookline, county of Norfolk and State of Massachusetts, have invented and produced a new and original Design for Printing-Types, of which the following is a specification.

The nature of my design, which I call "Card, Ornamented," is fully represented in the accompanying specimen impression, to which reference is made.

I claim as my invention—
The design for printing-types, as shown.
CARL SCHRAUBSTÄDTER.
